Specification of Letters Patent.

Patented Jan. 5, 1915.

Application filed May 20, 1914. Serial No. 839,718.

To all whom it may concern:

Be it known that I, SOL EINSTEIN, a citizen of the United States, and residing at Cincinnati, in the county of Hamilton and State of Ohio, have invented a new and Improved Centralized Automatic Control, of which the following specification is a full disclosure.

This invention deals with machine tools and it proposes various means whereby the construction of conventional machines may be simplified, a greater sturdiness may be imparted to the machine, and whereby its manipulations may be made very much more convenient to the attendant.

Among various other objects, this invention attains a reorganization and simplification of the scheme of transmission outlined by the U. S. Patent No. 1,092,479 issued to S. Einstein on April 7th, 1914, whereby a single automatic motion-reverser is enabled to execute all the functions of the two motion-reversers shown by said patent by reason of an arrangement which, at the same time, also enables fewer parts to be used with a resultant gain in structural simplicity, without sacrificing any of the advantages of the embodiment revealed in said patent.

Another object is to devise a construction and arrangement that will enable an automatic motion-reverser, an automatic shifter from "quick traverse" to "feed", and a hand-operable feed-changer to be compacted within a small compass in a very sturdy and efficient operative relationship.

Another object is to formulate, and combine with certain automatic features, a table-propelling mechanism in which a non-rotating screw, or its equivalent, may be utilized; thus, dispensing with the two journals required for the two ends of a rotatable screw, and in lieu thereof to use a rotating nut which requires but one journal; and thereby lower cost of manufacture and reduce the number of bearings to be lubricated.

Another object is to create a new arrangement with respect to the location of the various control features of the organization, so as to bring the control of the machine, as to all the urgent working operations, more immediately within reach of the attendant.

Other objects will be in part obvious from the annexed drawings and in part indicated

in connection therewith by the following analysis of this invention.

This invention accordingly consists in the features of construction, combination of parts and in the unique relations of the 60 members and in the relative proportioning and disposition thereof; all as more completely outlined herein.

To enable others skilled in the art so fully to comprehend the underlying features 65 thereof that they may embody the same by the numerous modifications in structure and relation contemplated by this invention, drawings depicting a preferred form have been annexed as a part of this disclosure, 70 and in such drawings, like characters of reference denote corresponding parts throughout all the views, of which:

Figure 1 is a side elevation of a milling machine embodying this invention; certain 75 parts being broken away to show details. Fig. 2 is a vertical section transverse to line 2-2 of Fig. 1 showing details of the construction of the combined saddle and feed-change box, and of the mounting of the 80 non-rotatable feed-screw, and of the motion-reverser, and of the means for shifting from "feed" to "quick-traverse", and conversely. Fig. 3 is a vertical section through line 3-3 of Fig. 2 showing further internal details 85 of the unit consisting of the feed-box and the saddle. Fig. 4 is a vertical section through line 4-4 of Fig. 2. Fig. 5 is a front elevation of the lower portion of the machine showing the arrangement of various control elements all located at the front and immediately accessible to the attendant; the parts being set to cause the table to feed to the left intermittently with quick-traverse movement, and then automatically 95 to return at a quick-traverse rate at the end of the stroke. Fig. 6 shows the manner in which the dogs are adjusted to effect a similar cycle of the table but in the opposite direction. Fig. 7 is a view of the table with 100 the dogs set thereon so as to execute what is known as "continuous milling." Fig. 8 is a side elevation showing the construction of a rotatable trip-member such as this invention proposes. Fig. 9 is a vertical section 105 through the said trip-member showing the arrangement whereby the continuous motion will be interpreted by an oscillating member. Fig. 10 is a plan of the trip-member showing the snap-back construction for 110

enabling the dogs to pass without ultimate tripping effect during their return passage. Fig. 11 is a plan showing more clearly the action of the trip-member in automatically effecting a shifting from a "quick-traverse" to a "feed". Fig. 12 is a side elevation showing details of the trip-mechanism for either stopping the travel of the table or for causing it to return at the rate it was moving at the end of its stroke. Fig. 13 is a plan showing details of the combined stop and motion-reverser with its trip-control; showing clearly the features for enabling the mechanism automatically to effect a stop, or to effect an automatic return by cutting out the stop. Fig. 14 is a section through line 13-13 of Fig. 13.

Continuing now by way of a more detailed description it may be stated at the outset that this invention contemplates a reciprocating milling machine table on which are adjustably mounted a plurality of stops or dogs which coöperate with a plurality of elements mounted in the path of travel of said dogs, and one of which has the function when actuated of changing the rate of travel of the table from a "feed" to a "quick traverse", or conversely, and another of which has the capacity of reversing the direction of travel of the table, causing the cutter to return either slowly over the work so as to refinish the same or rapidly to reach the starting point without loss of time.

To obtain an adequate understanding of this invention, it should be kept in mind that the term "feed", as used herein, indicates any one of a series of relatively slow movements of the table all essentially suitable for tooling operations, and the term "feed-changer" or "feed-change mechanism" indicates only that particular device which determines the rate at which the table thus "feeds"; and it is to be distinguished from variable speed devices which effect changes not all identified with a tooling-operation, as well as from the "speed-change mechanism" herein referred to and which determines the speed of rotation of the cutter-spindle. So also, the term "quick-traverse" is indicative of the rapid non-tooling movement by which the table travels over blank spaces; which motion usually represents the maximum speed at which the table may be moved and abruptly reversed, stopped or moderated to a "feed" without undue shock to the parts. It is desirable that this fast rate be a constant maximum for the sake of efficiency, and that it be unaffected by variations in the slow speed or "feed" of the table such as may be resorted to to meet different tooling conditions. Before detailing the specific features of construction whereby these functions are attained it will be convenient first to describe

certain major elements of a conventional milling machine. These comprise a table Y that supports the work and which is reciprocated to-and-fro to subject the work bolted thereon to the effect of the cutter that is secured to a spindle X which is continuously rotated by power derived from the same source or prime-mover that actuates the table. In order to enable the machine properly to execute its functions, these actuated elements must be capable of being brought into adjustable relation with one another in two directions. This is accomplished by an interponent frame-unit B that intervenes between the frame-unit A that directly supports the spindle and the frame-unit C that directly mounts the table. In the type of machine illustrated, the interponent frame-unit B is commonly termed a "knee"; the table-supporting frame-unit C is usually termed a "saddle", and the spindle mounting frame-unit A is generally termed a "column".

The chief mechanical characteristic of the interponent frame-unit or "knee" B is that it provides a relative vertical adjustment as to the spindle-mounting unit, and a horizontal adjustment as to the table-supporting unit, *i. e.*, in a direction transverse to the other. Thus, the "knee" B coöperates with the "saddle" C to move the table parallel with the axis of the spindle. The table Y rests on the saddle which in turn slides on the guide-ways 60 provided by the top portion of the knee; which guide-ways extend parallel with the spindle, as shown by Fig. 1. A screw-shaft 61 (see Fig. 5) is journaled in the knee and in the usual well-known way feeds the saddle through a suitable nut. This screw-shaft 61 may be rotated in a suitable way, as by means of the hand-wheel 62.

The spindle-mounting frame-unit or "column" A, has heretofore been that also selected to rest on the floor and thus provide a foundation for the machine, as a whole, and it has also been utilized to support or mount both the change-gear mechanism that varies the speed of the spindle, as well as the change-gear mechanism that varies the rate of feed of the table. This, however, has resulted in a very considerable inconvenience to the attendant in manipulating the machine. That is to say, the attendant must be stationed at the outer longitudinal side of the reciprocating table in order to scrutinize the action of the machine, but, when so stationed, he is out of reach of the levers that change the rate of feed of the table, so that in order to change this rate he must shift his position.

This invention proposes, among other things, a rearrangement and a reconstruction of the control elements so as to free the so-called "column" of the machine from the

mechanism that governs the rate at which the table shall feed, and so to locate the said mechanism, and so to combine it with other control features that the attendant, when stationed at the outer longitudinal edge of the reciprocating table, and without shifting his position, will be able, first, to change the rate at which the table feeds, *i. e.*, to vary its speed during a cutting-stroke; second, to cause the table to make a "quick-traverse"; *i. e.*, to shift quickly during a non-tooling interval; third, to change the direction of movement either of the "feed" or of the "quick-traverse"; 15 and fourth, to stop the movement of the table. In carrying out this aspect of this invention, one of the frame-units carrying the weight of the table may assume any conventional proportions or configuration, 20 such as are indicated on the drawings, but with this distinction, that it is contrived also to support or carry the weight of what may be termed a "feed-change" box, *i. e.*, the casing and elements constituting a change-gear mechanism such that the rate of "feed" may be varied at will. This box may also include other control features, such as the means for determining the direction of movement of the table, as well as the shift 25 30 for connecting the table either to "feed," or to make a "quick-traverse" as may be desired.

A more comprehensive grasp of the various aspects of this invention may perhaps be obtained by tracing the course of motion through the machine in connection with a description of the structural features involved.

At a convenient point, as for example on the column A, is mounted a prime-mover P, here instanced as a pulley, and both the spindle and the table may be driven by this prime-mover. Thus, the shaft ρ^1 , on which the pulley is mounted, may carry a number 40 45 of gears s^1 , s^2 , s^3 , and s^4 so that (through the hand-shifting means indicated by 5) any one of them may be caused to mesh with the appropriate one of the gears S^1 , S^2 , S^3 , and S^4 , respectively, so as to impart a predetermined rate of rotation to the shaft s^5 , thereby driving the pinion s^6 which, through an idler s^7 , drives a gear s^8 , which latter drives the spindle X. These parts are merely referred to as typifying any desired transmission from the prime-mover to the spindle that embodies a speed-change device; since it is obvious that various species of change-gears are equivalents of that illustrated.

Another transmission line derives motion 50 from the prime-mover and consists of the gear 1 meshing with pinion ρ^1 and also with a gear 2, which in turn rotates the universal and extensible shaft 3 that is connected to the universal joint 4 secured to a shaft 5 which is journaled in the box or casing C

and which terminates in a bevel 6 meshing with the two opposed bevels R and L. The bevel L, when utilized to transmit the power, causes the table to travel to the left; and the bevel R, when used, causes the table to travel to the right. The said transmission (consisting of the enumerated parts 1, 2, 3, 4, 5, 6, R and L) may be regarded as an intervening or trunk-line transmission, or it may in whole or in part be regarded as a portion 75 of the quick-traverse transmission.

A shiftable clutch member may be interlocked in driven relation with either the bevel R or the bevel L, and it in turn is splined to a sleeve b which is in turn keyed 80 to the shaft c so that the motion derived from either of the bevels is transmitted through the parts a, b and c; and, from the latter, two courses or paths are available for the motion: the one leading to the terminal-member QT (from which the quick-traverse motion is obtained), and the other to the terminal member F (from which the various rates of "feeds" are obtained); the first path may be termed the "quick-traverse" 90 transmission, and the second path may be termed the "feed transmission." Thus, in the quick-traverse transmission, the motion of the shaft c is imparted to a gear t that meshes with the terminal-gear QT. On the other hand, in the feed transmission, the motion of the shaft c is imparted, in the first instance, to the gear f and the latter rotates a series of gears f^1 , f^2 , f^3 and f^4 , any one of which may be caused to drive the shaft f^5 100 by meshing with the appropriate one of the gears F^1 , F^2 , F^3 and F^4 ; the selection of which is determined by the hand-shifting instrumentality E, which is essentially accessible to the attendant when stationed at the outer longitudinal edge of the table. The shaft f^5 rotates gear f^6 (see Fig. 4), and then the motion progresses through gears f^7 and f^8 to the terminal gear F. The series 110 of shifting gears constitutes what is herein termed a "feed-change mechanism T" and its relation to the other elements of this transmission is such that the terminal-gear F will be caused to rotate at the selected one of a series of speeds, all of which will be essentially slower than the speed of the terminal-gear QT, and all of which will be appropriate for use during some tooling period.

It is noteworthy that the speed and feed change mechanisms described in the foregoing are essentially of a self-contained or organized character, as distinguished from gears merely capable of bodily removal to permit of substitution.

A clutch or selector 7 is shiftable in interlocking engagement either with the "quick-traverse" terminal QT or with the "feed" terminal F, and motion is thereby imparted to the shaft 8 at a rate depending upon the position of the clutch 7 and, 120 130

through the gear 9, (which meshes with the gear 10) the nut 11 is driven. This nut is journaled in an adjacent portion of the table-supporting frame-unit and it is threaded to a feed-screw 12 which is non-rotatably keyed at its ends to the table Y, and the latter is, therefore, caused to travel at the rate and in the direction determined by the operation of the above described mechanism.

10 This transmission extending from the junction of the quick-traverse and the feed transmissions is in the nature of a short mechanical connection and it may be lengthened or shortened to any extent desired, and it may be regarded as including the table-propelling means, *e. g.*, the feed-screw or nut.

It is noteworthy that this system is simple and that but one motion-reverser is required, which is here located in a main trunk-line between the power and the junction of the feed transmission with the quick-traverse transmission. It may also be noted that this junction is considerably distanced 25 in the quick-traverse transmission from the end thereof nearest the table, thereby reducing the number of gears otherwise necessary to yield a sufficiently diminishing speed-ratio during the tooling operation of the 30 table; and it should also be observed that this junction is also located some distance from the prime-mover in such a way that a single chain of elements may act as a common carrier for the quick-traverse branch 35 as well as for the feed branch, thereby avoiding the duplication of elements inherent in two parallel lines of transmission.

The various structural improvements whereby the machine may automatically 40 execute the functions of stopping, reversing, and shifting from a quick-traverse to a feed, or conversely, may now be detailed.

The automatic stop contemplates a dog G adjustably or otherwise secured to the table 45 at an appropriate station, as by means of the bolt 13 and the T-slot 14. This dog G provides a contact surface in the form of a lug 15 which is adapted to impact a finger 16 projecting from the shift-lever H. This lever H provides a grip 17 whereby it may be actuated by hand, and it is secured to a shaft 18 journaled in a bracket 19 located at the side of the box C¹ most accessible to the attendant. Movements of this lever are 50 communicated to a lost-motion segment I (which is pivoted at 21) by means of a gear 20 secured to shaft 18 and meshing with gear teeth 22 on the segment I. Underlying this segment is a Y-shaped lever J, also pivoted at 21, which derives motion from the pin 23 depending from segment I and in turn shifts the clutch x by means of its finger 24. This pin has a small play in its slot sufficient to permit a limited positive 55 movement of the lever H (under dog-ac-

tion) without causing breakage, should the clutch teeth not happen to be in meshing relation at the instant of initial contact. The effect of this halfway positive motion is to cause the spring-pressed V-shaped plunger K to ride over the peak 25 and thus be enabled impositively to execute the second half of the swing of the lever H and the segment I whenever the clutch teeth come into intermeshing relation; provided however that a certain stop-device is in its releasing position. This stop-device M comprises a rock-shaft 26 that carries a pawl 27 projecting over the edge 28 of the Y-shaped lever J. A notch 29 is cut in this lever at 60 a point such that when the lever holds the clutch x disengaged from both bevels R and L, then the pawl 27 will enter the notch 29 and continue to hold the parts in this position until the pawl is withdrawn either automatically or by hand.

The automatic motion-reverser contemplates a dog N which is complementary or similar to the dog G in all respects save that it embodies a second contact-surface 30 located in a different path of travel than the lug 15. This contact-surface 30 impacts a suitable contact-surface 31 and this appropriately actuates a reverser which is here instanced as a plunger 50 normally held in elevated position by the spring 32. The effect of this impact is to depress the plunger 50 and through the intermeshing gear teeth 33 so to swing the rock-shaft M as to raise the pawl 27 out of the notch 29. Thereupon, 65 the pressure in the meantime exerted by the spring 34 becomes effective through the wedge K to complete the throw of the lever J in whatever direction it may have been partway moved by the lever H, and thus bring the clutch x into driven relation with either the bevel R or L and thereby effect 70 a reversal in the motion transmitted.

The automatic quick-traverser includes an adjustable dog such as the one that first executes a tripping function as the table travels to the left, as shown by Fig. 5. This dog is indicated by O-- (indicating that it effects a quick-traverse to the left or in a negative direction of the table), and is distinguished 75 in effect from the dog O+ in that the latter effects a quick-traverse of the table to the right or in a positive direction. These dogs differ in construction as will presently appear. A dog O-- is shown in side elevation 80 by Fig. 8 and it is adjustable longitudinally of the table by means of the headed bolt 35 and it provides a contact-surface 36 in the nature of a small depending lug located in offset relation with the axis of the trip member, *i. e.*, on the side of the axis other than that of the path of travel of the dog O+. The tripped member U comprises a vertical shaft 37 (Fig. 9) journaled in a bracket 85 38, or located with relation to the box C¹, so 90

as to position the trip at the front or accessible edge of the table. The upper end of this shaft terminates in a journal 39 on which is loosely pivoted a star-wheel 40, which has an inner groove 41 terminating in a shoulder 42, and, by means of the expansive spring 43, this star-wheel is normally maintained with the shoulder 42 against a pin 44 projecting from the journal 39. The effect of this construction is to permit the star-wheel to be rotated anti-clock-wise for say—nearly ninety degrees—without turning the shaft 37 (thus permitting a dog to return without making an effective trip), but all motions clock-wise of the star-wheel 40 are positively imparted to the shaft 37. Now, starting from the position shown by Fig. 5, the dog O— travels to the left until it impacts the contact surface $\circ$ of the star-wheel 40, thereby turning the same clock-wise through a definite predetermined angle (here 90°), thus correspondingly rotating the gear 45 secured to the end of the shaft 37. This gear meshes with a pinion 46, and the gear ratio is such that the pinion 46 will rotate through 180° during the predetermined rotation of the gear 45. This pinion carries a depending pin 47 that enters a slot 48 in a segment V pivoted at 49 (Fig. 11), and which in turn carries a pin 50 that engages with a Y-shaped lever W by means of a slot 51 providing for lost motion. This lever W in turn determines the position of a clutch 7, and, with the parts as shown on the drawings, the clutch 7 now engages the terminal gear F and the table is feeding to the left as appears from Figs. 5 and 7; Fig. 6 being an exception. The construction of the parts V and W is similar to that used in connection with the automatic stop and motion reverser and need not be detailed. It will be seen from this that the effect of the impact of the dog O— with the contact surface $\circ$ is to shift the clutch 7 from the gear F to the gear QT; thus, changing the motion of the table from a feed to a quick-traverse, without, however, changing its direction of movement.

The automatic feeder embodies all of the elements mentioned with respect to the quick-traverse with the exception of the location of the dog O— with relation to the position of the star-wheel. In other words, a dog Z $^+$, which is structurally identical with the dog O—, is nevertheless, now capable of changing the travel of the table from a quick-traverse to a feed by reason of the fact that its contact surface is now enabled to impact the contact surface $\circ$ of the star-wheel, and thus give it an additional turn, also clock-wise, through the predetermined angle, thereby turning the gear 46 through another half revolution and bringing the pin 47 to its other extreme position

with the effect of bringing the clutch 7 back into the position shown on Fig. 11, thereby causing the table to feed.

The automatic operation of the parts as arranged according to Fig. 5 may now be understood, and is as follows: Table is feeding to the left. Dog O— then impacts star-wheel and causes table to make a quick-traverse to the left. Dog Z $^+$ restores initial position of star-wheel and table again feeds to left. Dog O $^+$ now turns star-wheel to make a quick-traverse of the table. Then contact surfaces 15 and 30 of dog N $^+$ clear the star-wheel, which is constructed to permit of its so doing, and the contact surface 30 actuates the plunger 50 to render the reverser operative so that, when the contact surface 15 impacts the lever H, the clutch a will be shifted to engage bevel R, and the table will now be moved to the right and will continue doing so until the dog G again shifts the position of the lever H to the neutral or stopping point. The machine may now be started by hand by simply turning the part M, thereby enabling lever H to complete its stroke in the direction initiated by the dog G; thus, starting the table to the left and at the rate determined by the trip dog O $^+$ — which last acted on the star-wheel.

The same automatic actions may be given the table in the converse order as will best be understood by referring to Fig. 6. In this figure, the star-wheel is in the same position as in Fig. 5, but the reverser is in a different position and the table is feeding to the right to bring the dog O $^+$ against the star-wheel. It is to be noted that this dog has its contact surface traveling at the inner side of the axis of the star-wheel, whereas the dog O— operates at the outer side. The dog O $^+$, therefore when moving to the right turns the star-wheel in the same direction as the dog O— when the latter travels to the left. The impact of dog O $^+$, therefore, imparts a quick-traverse to the right to the table; which is again reduced to a feed by the impact of the dog Z $^+$; and it again is converted to a quick-traverse by the impact of the dog O $^+$; until the dog N $^+$ depresses the plunger 50 and shifts the lever H, and thus reverses the motion of the table without changing its speed. Ultimately the dog G stops the table and it may then be started by hand.

The continuous milling may be effected by the arrangement shown in Fig. 7, as follows: Assuming that dog N $^+$ has just operated to start the table to the left, its rate will be that determined by the effect of the last acting dog (here a quick-traverse) so that the table will speed to the left until dog Z— trips the star-wheel; then it will travel to the left until dog O— trips the star-wheel; then it will make a quick-traverse to the left

until dog Z^1 — trips the star-wheel; then it will feed to the left until dog O^1 — trip the star-wheel and imparts a quick-traverse still to the left to the table. These successive impacts have all turned the star-wheel clockwise. When the dog N^1 contacts with the lever H the motion will be reversed without changing the rate and the table will make a quick-traverse to the right until dog Z^2 — turns the star-wheel clockwise and the table will then feed to the right. The cycle will be repeated through the dogs O^2 , Z^2 , O^3 — and N^2 ; the table continuously reciprocating from left to right and executing variations in its rate of travel during each stroke in accordance with the adjustment of the various dogs.

Having thus revealed this invention, I claim as new and desire to secure by Letters 20 Patent of the United States:

1. A machine-tool combining a spindle; a table positioned thereunder adapted to reciprocate transversely to said spindle; frame-units for mounting said spindle and table in said relation, and providing a relative adjustment between said table and spindle in a direction parallel with the axis of the spindle and also enabling the vertical distance between said spindle and table to be adjusted; a prime-mover supported by one of said frame-units; a speed-change mechanism carried by the frame unit supporting the spindle and in intervening relation with said prime-mover and said spindle; a first transmission establishing driving relation between said prime-mover and said spindle through said speed-change mechanism; a feed-change mechanism carried directly by another one of said frame-units and located below said table, and having its gear-shift lever accessible from the forward side of said table; a second transmission deriving from said prime-mover motion unaffected by either said speed change or said feed-change mechanisms, and adapted to be brought into propelling connection with said table to effect a quick traverse thereof; a third transmission extended through said feed-change mechanism and deriving motion from said prime mover; a shifting means for rendering said second transmission ineffective to propel said table independently of said third transmission, and for enabling the motion of said table to be effected through said third transmission; and a motion-reverser in serial relation with each of said transmissions.

2. A machine-tool organization combining a table; a trip-member arranged adjacent thereto and providing contact surfaces located at opposite sides of its axis of movement; a first dog movable with said table and having a contact surface adapted to impact a contact surface on one side of the axis of said trip-member and move it in one

direction during an advance of said table; a second dog movable with said table and having a contact surface adapted to impact a contact surface on the other side of the axis of said trip-member and also move it in the aforesaid direction during a retreat of said table; and means for propelling said table in accordance with the angular position of said trip-member.

3. A unitary machine-tool organization combining a spindle; a table; a prime-mover; a speed-change mechanism between the spindle and the prime-mover; a first transmission connecting said spindle and said prime-mover through said speed-change mechanism; a feed-change mechanism; a motion-reverser intervening between said prime-mover and said feed-change mechanism; a second transmission adapted to connect said prime-mover, said motion-reverser, said feed-change mechanism and said table together in series in said sequence; a third transmission connected to said second transmission between said motion-reverser and said feed-change mechanism to impart a quick-traverse to said table at a rate independent of the condition of said feed-change mechanism; and shifting means adapted to render said third transmission inoperative to impart a quick-traverse to said table and to render said second transmission operative to cause said table to feed at a rate determined by said feed-change mechanism.

4. A unitary machine tool organization combining a prime-mover; a reciprocating table; a non-rotatable feed-screw carried by said table to translate therewith; a table-support; a rotatable nut carried by said table-support and co-operating with said feed-screw; a feed-change mechanism intervening between said prime-mover and said table; a transmission extending from said prime-mover exclusive of said feed-change mechanism and ending in a terminal member located adjacent said nut; a second transmission including said feed-change mechanism and also deriving motion from said prime-mover and ending in a second terminal-member located adjacent said nut; a connecting instrumentality for establishing an operative mechanical connection between either said first terminal-member and said nut to rotate it at a rate determined by said feed-change mechanism or between said second terminal-member and said nut to enable it to impart a quick-traverse to said table at a rate independent of the condition of said feed-change mechanism.

5. A machine-tool organization combining two actuated elements, the one being a table and the other being a spindle; a first and a second frame-unit, one of said frame-units supporting the spindle and the other supporting the table; an intermediate frame-unit having a vertically adjustable connec-

- tion with the first frame-unit and also having a horizontally adjustable connection with the second frame-unit, one of said frame-units and also the weight of one of said actuated elements being both supported by another of said frame-units; a variable-speed mechanism carried directly by said last-mentioned frame-unit and geared to actuate the said element supported thereby; and another organized variable speed mechanism carried directly by one of said other frame-units and geared to said other element to effect a quick-traverse or a feed thereof, and also providing a hand-operating part located adjacent said last-mentioned element; and a prime-mover carried by one of said frame-units and geared to each of said variable-speed mechanisms.
6. A machine-tool organization combining a table; a trip-member arranged adjacent thereto and providing contact surfaces located at opposite sides of its axis of movement; a first dog movable with said table and having a contact surface adapted to impact a contact surface on one side of the axis of said trip-member and move it in one direction during an advance of said table; a second dog movable with said table and having a contact surface adapted to impact a contact surface on the other side of the axis of said trip-member and also move it in the aforesaid direction during a retreat of said table; a part moved to-and-fro by said member during two successive angular advances thereof; clutch mechanism actuated by said part; and means controlled by said clutch-mechanism for propelling said table rapidly or slowly.
7. A unitary machine-tool organization combining a spindle; a table; a prime-mover; a speed-change mechanism between the spindle and the prime-mover; a feed-change mechanism and a motion-reverser between the table and the prime-mover; a first transmission connecting said spindle and said prime-mover through said speed-change mechanism; a second transmission adapted to connect said table, said motion-reverser, said feed-change mechanism and said prime-mover together in series; a third transmission connected to said second transmission between said motion-reverser and said feed-change mechanism and shunting said feed-change mechanism to impart a quick-traverse to said table at a rate independent of the condition of said feed-change mechanism; and shifting means adapted to interrupt said third transmission and to establish a mechanical connection between said prime-mover and said table through said second transmission, whereby it may cause said table to feed at a rate determined by said feed-change mechanism.
8. A unitary machine-tool of the nature disclosed, combining a spindle; a table posi-
- tioned thereunder adapted to reciprocate transversely to said spindle; frame-units for mounting said spindle and table in said relation, and providing a relative adjustment between said table and spindle in a direction parallel with the axis of the spindle and also enabling the vertical distance between said spindle and table to be adjusted; a prime-mover supported by one of said frame-units; an organized speed-change mechanism intervening between said prime-mover and said spindle; a first transmission establishing driving relation between said prime-mover and said spindle through said speed-change mechanism; an organized feed-change mechanism carried directly by the table-supporting unit and located below said table, and having its gear-shift lever arranged adjacent said table; and a second transmission deriving from said prime-mover motion unaffected by said first mentioned speed-change mechanism and extending through said feed-change mechanism into connection with said table to reciprocate it either at a quick-traverse rate or at a rate of feed determined by the said feed-change mechanism.
9. A machine-tool organization combining a table; a series of similar dogs arranged in a row thereon; a rotatable trip-member adapted to be turned progressively through equal predetermined angles by the successive impacts of said dogs; a shift-element connected with said trip-member to be moved positively thereby when it is turned in one direction, and unaffected by said trip-member when it is turned in the opposite direction; a rapidly driven part; a slowly driven part; a table-propelling means; and means actuated by said shift-element for establishing an operative connection of either of said parts with said table-propelling means.
10. A unitary machine-tool organization combining a spindle; a table; a table-propelling means; a prime-mover; a speed-change mechanism between the spindle and the prime-mover; a first transmission connecting said spindle and said prime-mover through said speed-change mechanism; a second transmission connecting said prime-mover, said motion-reverser, said shift-device and said table-propelling means in series in the order recited; a feed-change mechanism; a third transmission connected to said second transmission between said motion-reverser and said shift-device and extending through said feed-change mechanism, said shift-device being adapted to interrupt the transmitting capacity of said second transmission and to establish an operative mechanical connection between said prime-mover and said table through said third transmission, whereby said table may be caused to feed.

at a rate determined by said feed-change mechanism and in the direction determined by said motion-reverser.

11. A machine-tool organization combining a reciprocating table; a table-support; a feed-screw; a gear in threaded relation with said feed-screw and constituting a gear-nut therefor, said feed-screw being non-rotatively secured to one of said parts and 5 said nut being rotatively secured to the other; an interponent gear permanently meshing with said gear-nut; a power-driven quick-traverse transmission ending in a terminal-member located adjacent said interponent gear; a table-feed transmission including a feed-change mechanism also ending in an adjacent terminal-member; and means for establishing a driving relation between said interponent gear and either of 10 said terminal-members.

12. A machine-tool organization combining a table; a series of similar dogs arranged in a row thereon; a rotatable trip-member adapted to be turned progressively through 15 equal predetermined angles by the successive impacts of said dogs; a rotatable shift-element connected with said trip-member to be moved positively thereby when it is turned in one direction, and unaffected by 20 said trip-member when it is turned in the opposite direction; a rapidly driven part; a slowly driven part; a table-propelling means; an element periodically oscillated by said rotatable shift-element; and means 25 actuated by said element for establishing an operative connection of either of said parts with said table-propelling means.

13. A machine-tool organization combining a reciprocating member constituting a 30 table; a relatively stationary member constituting a table support; a threaded element constituting a feed-screw; a second element in threaded relation with said feed-screw and constituting a nut therefor; one 35 of said elements being non-rotatively secured to one of said members and the other of said elements being rotatively secured to the other member; a gear secured to said last-mentioned element; an interponent gear 40 permanently meshing with said gear; a power-driven quick-traverse transmission ending in a terminal member located adjacent said gear; a feed transmission including a feed-change mechanism also ending 45 in an adjacent terminal-member; and means for establishing a driving relation between said interponent gear and either of said 50 terminal-members.

14. A machine-tool of the nature disclosed 55 combining a spindle; a table positioned thereunder adapted to reciprocate transversely to said spindle; frame-units for mounting said spindle and table in said relation, and providing a relative adjustment 60 between said table and spindle in a direc- 65

tion parallel with the axis of the spindle and also enabling the vertical distance between said spindle and table to be adjusted; a prime-mover supported by one of said frame-units; a speed-change mechanism carried by the frame-element supporting the spindle and in intervening relation with said prime-mover and said spindle; a first transmission establishing driving relation between said prime-mover and said spindle 70 through said speed-change mechanism; an organized feed-change mechanism carried directly by another one of said frame-units and located below said table, and having its gear-shift lever accessible from the forward side of said table; and a second transmission deriving from said prime-mover motion unaffected by said organized first mentioned speed-change mechanism and extending through said feed-change mechanism into 75 propelling connection with said table to reciprocate it either at a quick-traverse rate or at a rate of feed determined by the said feed-change mechanism.

15. An automatic table-propelling mechanism combining an advancing table; a rotary member adjacent said table and providing different contact surfaces; a first dog movable with said table adapted to impact one of said contact surfaces to rotate said member into one position; a second dog movable with said table adapted to impact the other of said contact surfaces further to rotate said member into another position, a propelling mechanism for imparting fast or 90 slow speed to said table, and a shift mechanism controlled by said member and adapted on one position thereof to cause said propelling mechanism slowly to advance 95 said table, and in another position thereof rapidly to advance said table.

16. An automatic table-propelling mechanism combining an advancing table; a member adjacent said table and providing different contact surfaces located in the same 110 plane; a first dog movable in said plane with said table adapted to impact one of said contact surfaces to move said member into one position; a second dog movable also in said plane with said table adapted to impact the other of said contact surfaces to move 115 said member into another position; a propelling mechanism normally adapted slowly to propel said table; means interchangeably available with a portion of said mechanism 120 and adapted greatly to increase the propelling capacity of said mechanism; and a shift instrumentality controlled by said member and adapted in one position thereof to render said means ineffective and in another 125 position to render it effective.

17. An automatic table-propelling mechanism combining an advancing table; a trip-instrumentality adjacent said table and rotatable progressively into different posi- 130

- tions; a first dog movable with said table adapted when advancing therewith to impact said trip instrumentality and rotate it into one position; a second dog movable with 5 said table adapted also when advancing therewith to impact and further rotate it into another position, a propelling mechanism for imparting fast or slow speeds to said table; and a shift mechanism controlled by said instrumentality and adapted in one dog-determined position thereof to cause 10 said propelling mechanism slowly to advance said table, and in the next succeeding dog-determined position thereof rapidly to 15 advance said table.
18. A machine-tool of the nature disclosed combining a spindle; a table positioned thereunder adapted to reciprocate transversely to said spindle; frame-units for 20 mounting said spindle and table in said relation, and providing a relative adjustment between said table and spindle in a direction parallel with the axis of the spindle and also enabling the vertical distance between 25 said spindle and table to be adjusted; a prime-mover supported by one of said frame-units; a speed-change mechanism carried by the frame-unit supporting the spindle and in intervening relation with said 30 prime-mover and said spindle; a first transmission establishing driving relation between said prime-mover and said spindle through said speed-change mechanism; a feed-change mechanism carried directly by 35 another one of said frame-units and located below said table, and having its gear-shift lever accessible from the forward side of said table; a second transmission deriving from said prime-mover motion unaffected by 40 said first mentioned speed-change mechanism and extending through said feed-change mechanism and adapted to be brought into propelling connection with said table to feed it at a rate determined by the 45 said feed-change mechanism; a third transmission deriving from said second transmission motion unaffected by said feed-change mechanism; and a shift device available to disconnect the second transmission from said 50 table and to connect the third transmission therewith to effect a quick-traverse of said table independently of said second transmission.
19. An automatic table-propelling mechanism combining an advancing table; a trip instrumentality adjacent said table and movable progressively into different positions; a first dog movable with said table adapted when advancing therewith to impact 55 said trip instrumentality and move it into one position; a second dog movable with said table adapted also when advancing therewith to impact and further move it into another position; a propelling mechanism normally adapted slowly to propel 60 said table; means abruptly adapted greatly to increase the propelling capacity of said mechanism; and a shift device oscillated by the progressive movement of said instrumentality and adapted in one dog-determined position thereof to render said means ineffective and in the next succeeding dog-determined position to render it effective.
20. An automatic table-propelling mechanism combining an advancing table; a progressively rotatable trip instrumentality adjacent said table and movable into different successive positions; a first dog movable with said table adapted when advancing therewith to impact said trip instrumentality and move it into one position; a second dog movable with said table adapted also when advancing therewith to impact and move it into another position; a non-retatable screw longitudinally movable with said table; a rotatable nut threaded on said screw and confined against longitudinal movement; means for causing a slow relative movement between the screw and nut; means for abruptly increasing said relative movement; and mechanism controlled by said instrumentality and adapted in one dog-determined position thereof to render effective only the first mentioned means, and adapted in another dog-determined position to render effective the second mentioned means.
21. An automatic table-propelling mechanism combining an advancing table; a progressively rotatable fast-slow trip-instrumentality adjacent said table; a reversing trip-instrumentality also adjacent said table; table-propelling mechanism having its capacity determined by said instrumentality, and dogs movable with said table for automatically progressively shifting the fast-slow trip-instrumentality into successive positions, and for subsequently shifting the reversing trip-instrumentality.
22. An automatic table-propelling mechanism combining a movable table; table-propelling mechanism; two independently movable trip-devices adjacent said table, one of said trip-devices providing a plurality of equispaced contact surfaces; a number of dogs movable with said table each having a contact surface whereby said last mentioned trip-device will be actuated progressively into different positions by the advance passage of said dogs; means for causing said propelling-mechanism to actuate the table rapidly or slowly according to the position of said last mentioned trip-device; and means for determining the direction of operation of said mechanism in accordance with the position of the other trip-device.
23. An automatic table-propelling mechanism combining a movable table; table-propelling mechanism; two independently

movable trip-devices adjacent said table, one of said trip-devices providing a plurality of contact surfaces each equispaced apart and each equidistant from the center of rotation of said trip-device; a number of dogs rigid with said table and each providing a contact surface movable in a path of travel intersecting that of said trip-device, whereby said device will be effectively actuated by said device will be effectively actuated
10 progressively into different positions by the advance passage only of said dogs, and whereby said trip-device be ineffectively actuated during the return passage only of said dogs; means for causing said propelling-mechanism to actuate the table rapidly
15 or slowly according to the position of said last mentioned trip-device; means for determining the direction of operation of said mechanism in accordance with the position of the other trip-device, and a dog having a 20 contact surface movable in another path of travel for actuating said other trip-device.

In witness whereof, I hereunto subscribe my name, as attested by the two subscribing witnesses.

SOL EINSTEIN.
